CLAIM

The ornamental design for an electronic device holder, as shown and described.

DESCRIPTION

FIG. 1 is a perspective view of an electronic device holder showing our new design according to a first embodiment; FIG. 2 is another perspective view of the first embodiment; FIG. 3 is a front elevational view of the first embodiment; FIG. 4 is a right side elevational view of the first embodiment;

FIG. 5 is a left side elevational view of the first embodiment; FIG. 6 is a rear elevational view of the first embodiment; FIG. 7 is a sectional view of the first embodiment taken along line 7-7 of FIG. 3;

FIG. 8 is a sectional view of the first embodiment taken along line 8-8 of FIG. 3; and,

FIG. 9 is a front elevational view of the electronic device holder showing our new design according to a second embodiment, the second embodiment being identical to the first embodiment except that the second embodiment includes two sets of broken lines which indicate that no particular length is claimed.

The broken lines in FIGS. 1-9 depict environmental structure that form no part of the claimed design. The areas encircled by broken lines in FIGS. 1-3, 6 and 8-9 depict environmental structure that form no part of the claimed design.
